UNITED STATES PATENT OFFICE.

SVEN EMIL SIEURIN, OF HÖGANÄS, SWEDEN.

BURNING OF CARBON ELECTRODES.

1,390,823.

Specification of Letters Patent. Patented Sept. 13, 1921.

Application filed July 31, 1920. Serial No. 400,514.

To all whom it may concern:

Be it known that I, SVEN EMIL SIEURIN, a subject of the King of Sweden, residing at Höganäs, Sweden, have invented new and 5 useful Improvements in the Burning of Carbon Electrodes, (for which I have filed an application in Sweden on Sept. 16, 1918,) of which the following is a specification.

This invention relates to an improved 10 process and apparatus for producing carbon electrodes in an electric furnace, the principal object of the invention being to provide a process and apparatus by means of which the gasification of the volatile components of 15 the electrode may take place from the exterior toward the interior of the electrode, thereby permitting the deposit on the electrode of the graphite resulting from the gases, and by means of which apparatus the 20 resulting electrode is without cavities such as are ordinarily produced by the insertion of a metal core in the material from which the electrode is formed.

In the drawings accompanying and forming part of this specification,

Figure 1 is a fragmentary sectional view of an electric furnace adapted for carrying out the present invention; and Fig. 2 is a similar view illustrating a modified form of 30 metallic member for initiating the burning of the carbon electrodes.

The same characters of reference designate the same parts in the different figures of the drawings.

In the manufacture of carbon electrodes which are usually produced by the calcination in an electric furnace of a plastic mass of coke or other carbonaceous material and a binding substance, for instance, tar, it has 35 heretofore been the practice to place one or more metal cores, usually of iron, within the carbonaceous mass from which the electrode is to be formed, said cores being surrounded by an insulating, fireproof material. The 40 purpose of these cores is to act as conductors for the electric current until the carbonaceous mass has been sufficiently burned so that it becomes itself a conductor, and as soon as the temperature in the furnace becomes 45 sufficiently high the metal cores are melted. This procedure has the disadvantage that the electrodes produced will be partially intermixed with the metal of the fused or melted core and thereby rendered 50 unsuitable for the production of aluminum, for instance. Moreover, by reason of the

melting of the metal cores, cavities are formed within the electrodes, and the gasification of the volatile components of the electrodes takes place from the interior thereof 60 outwardly, that is to say, from the hottest part of the electrode toward the coolest part, which is undesirable, because it does not permit the depositing of the graphite resulting from the gases upon the surface of the electrode, which deposit of graphite is very 65 advantageous for the reason that it increases the conductivity of the electrode.

In order to overcome the disadvantages above referred to, the present invention provides a process and apparatus by means of which the plastic mass which is to be burned is inclosed within a jacket of insulating material and the metallic heat initiating means is disposed outside of said mass and separated therefrom by said insulating material.

Referring to the drawings, 1 designates the furnace, within which are placed the blocks 2 of plastic material to be burned, each block being incased in a jacket 3 of 80 insulating material. As illustrated in Fig. 1, the metallic means for initiating the heating of the block is in the form of rods 4 embedded in the walls of the insulating jacket, while in Fig. 2 the initial heating member 85 is illustrated as formed of a metal tube 5 inclosing the insulating jacket. It will, of course, be understood that the metal tube 5 may, if preferred, be embedded in the walls of the insulating jacket in the same manner 90 as the rods 4 of Fig. 1. In both forms illustrated, as soon as the plastic blocks have been sufficiently burned so that they have become conductive, the metal members may be removed from the furnace and the burning 95 continued through the instrumentality of the plastic blocks themselves. It will thus be seen that by this procedure each of the blocks forms an electrode without cavities formed by the metal members and owing 100 to the fact that the heating begins at the outside, the gasification of the volatile components of the blocks also proceeds from the outside toward the center, thus permitting the deposit of the graphite from the gases 105 on the surface of the electrodes.

Having thus described my invention, what I claim is:

1. The process of producing a carbon electrode which consists in placing a mass of 110 electrode forming material in an electric furnace, surrounding the same with metal-

lic heat initiating means insulated therefrom, passing a current through said means to heat said mass to a predetermined degree, removing said heat-initiating means and continuing the heating through the instrumentality of the mass itself.

2. The process of producing a carbon electrode which consists in placing a mass of electrode forming material in a jacket of insulating material in an electric furnace, passing a current through metallic heat initiating means associated with said jacket and heating said mass until it becomes conductive, removing said heating means, and continuing the heating through the mass itself.
- 10 3. An apparatus for burning carbon elec-

trodes, comprising an electric furnace, metallic heat initiating means in said furnace for each electrode to be burned, and an insulating jacket associated with said heat initiating means and adapted to receive the electrode forming material.

4. An apparatus for burning carbon electrodes, comprising an electric furnace, a metal jacket in said furnace for each electrode to be burned, and an insulating jacket within said metal jacket and adapted to receive the electrode forming material.

In testimony whereof I have signed my name to this specification.

SVEN EMIL SIEURIN.
